PORTABLE ICE BOX

Herbert S. Jones, 300 NW. 18th Ave.,
Miami, Fla. 33125

Filed Mar. 18, 1968, Ser. No. 11,008

Term of patent 14 years

Int. Cl. D15—11

U.S. Cl. D67—3

FIG. 1

The rear of the box is identical to the front.

The dominant features of my design reside in the portions shown in full lines.

I claim:

The ornamental design for a portable ice box, substantially as shown and described.
